CLAIM

I claim the ornamental design for a bar-b-que grill, as shown.

DESCRIPTION

FIG. 1 is a front elevational view of a bar-b-que grill showing my new design;

FIG. 2 is a front elevational view thereof with portions shown in an open position;

FIG. 3 is a top plan view thereof;

FIG. 4 is a bottom plan view thereof;

FIG. 5 is a right end elevational view thereof;

FIG. 6 is a rear elevational view thereof;

FIG. 7 is a perspective view thereof;

FIG. 8 is a perspective view thereof with portions shown in an open position; and,

FIG. 9 is a left end elevational view thereof.

1 Claim, 4 Drawing SheetsFIG. 1.

FIG. 2.

FIG. 3.

FIG. 4.

FIG. 5.

FIG. 6.

FIG. 7.

FIG. 8.

FIG. 9.
